Primary Examiner — Janice Hallmark*Assistant Examiner* — Harold E Blackwell, II(74) *Attorney, Agent, or Firm* — Haynes and Boone, LLP(57) **CLAIM**

The ornamental design for the suction cup mount, as shown and described.

DESCRIPTION

FIG. 1 shows a front perspective view of a suction cup mount;

FIG. 2 shows a front view of a suction cup mount of FIG. 1;

FIG. 3 shows a rear view of the suction cup mount of FIG. 1;

FIG. 4 shows a right view of the suction cup mount of FIG. 1;

FIG. 5 shows a left view of the suction cup mount of FIG. 1;

FIG. 6 shows a top view of the suction cup mount of FIG. 1; and,

FIG. 7 shows a bottom view of the suction cup mount of FIG. 1.
